COMBINED DESK, CLOTHES CABINET, AND MAGAZINE RACK

Rhoda Selden Silverman, New York, N. Y.

Application January 12, 1954, Serial No. 28,492

Term of patent 7 years

(Cl. D33—7)

To all whom it may concern:

Be it known that I, Rhoda Selden Silverman, a citizen of the United States of America and a resident of the city of New York, in the county of Nassau and State of New York, have invented a new, original, and ornamental Design for Combined Desk, Clothes Cabinet, and Magazine Rack, of which the following is a specification, reference being had to the accompanying drawing, forming a part thereof.

Fig. 1 is a front perspective view, taken from the right side, of a combined desk, clothes cabinet, and magazine rack, showing my new design; and

Fig. 2 is a front perspective view of the design shown in Fig. 1 with the cabinet doors in an open position.

I claim:

The ornamental design for a combined desk, clothes cabinet, and magazine rack, substantially as shown.
